US0D1062698S

(12) **United States Design Patent** (10) **Patent No.:** **US D1,062,698 S**
(45) **Date of Patent:** **** Feb. 18, 2025**

(54) **AUDIO DEVICE POUCH**

(71) Applicant: **Rad Golf, Inc.**, Scottsdale, AZ (US)

(72) Inventors: **Peter Johnson**, Phoenix, AZ (US);
Altino Alexandre Cordeiro Neto, San
Diego, CA (US)

(73) Assignee: **RAD GOLF, Inc.**, Scottsdale, AZ (US)

(**) Term: **15 Years**

(21) Appl. No.: **29/905,918**

(22) Filed: **Oct. 27, 2023**

(51) LOC (15) Cl. **14-03**

(52) U.S. Cl.

CLAIM

The ornamental design for an audio device pouch, as shown and described.

DESCRIPTION

FIG. 1 is a perspective view of an audio device pouch.

FIG. 2 is a second perspective view thereof with environment.

FIG. 3 is a front view thereof.

FIG. 4 is a rear view thereof.

FIG. 5 is a left-side view thereof.

FIG. 6 is a right-side view thereof.

FIG. 7 is a top view thereof; and,

FIG. 8 is a bottom view thereof.

(Continued)

The broken line showing of parts of the drawings is included for the purpose of illustrating use and environment, and forms no part of the claimed design.

1 Claim, 6 Drawing Sheets
